UNITED STATES PATENT OFFICE.

FRANK HERNAMAN COTHAY, OF LONDON, ENGLAND, ASSIGNOR OF ONE-HALF TO ROFF TIN LIMITED, OF LONDON, ENGLAND, A BRITISH COMPANY.

BUCKET AND BUCKET ELEVATOR AND DREDGE.

Application filed June 8, 1927, Serial No. 197,438, and in Great Britain September 29, 1926.

This invention comprises improvements in or relating to buckets and bucket elevators and dredges.

It is well known that a bucket which is filled with stiff plastic material which is impervious to air, such as wet clay or like sticky plastic material cannot be easily emptied. For example, in the use of bucket elevators for dredging operations where these have to be employed on clayey material, the buckets of the elevator frequently become filled with clay which refuses to fall out of the buckets when these reach the discharging point of the elevator, with the consequence that as soon as a substantial proportion of the buckets are thus choked, the elevator has to be stopped and all the buckets cleared by hand which is not only laborious but a serious waste of time. It has been attempted to remove clay from the buckets by means of water-jets at high pressure directed upon the material therein with the object of sluicing them out while they are in motion, but this plan is not wholly successful, as the water-jets tend to merely cut holes in the clay and not to remove the clay from the bucket bodily in the limited time available during the passage of each bucket. In consequence the usual practice when digging clay is to fill the bucket partially only. It is an object of the invention to avoid this difficulty and to enable the buckets to be filled full and readily discharged.

According to the present invention a method of removing materials of the kind described from buckets, consists in introducing water under pressure to the interior of the bottom of the bucket behind or underneath the material to be removed.

The invention comprises the provision of a passage for admission of water which extends down the side of the bucket and opens into its interior near the bottom, for the purpose of admitting water to the interior of the bucket at the bottom and allowing it to act upon clayey or like materials therein to loosen them and facilitate their removal.

As applied to a bucket elevator or dredge, the invention comprises the combination of a chain of buckets, channels in the buckets which are provided with mouths outside the buckets and which extend from the mouths to the interior of the buckets near the bottoms

thereof, and a water-jet situated at the point of discharge of the chain for directing water into the buckets. When the buckets arrive at the point of discharge they are inverted and the water entering through the channels and loosening the clay and acting by pressure behind it, help to force it out of the bucket.

Means hereinafter described may be provided for moving the water-jet during the passage of each bucket past the jet so as to lengthen the period of impingement of the jet upon the mouths of the channels.

The accompanying drawings illustrate various examples of constructions of bucket elevator in accordance with the invention.

In the drawings:—

Figure 1 is a side elevation of the upper tumbler and associated parts of a bucket elevator or dredge to which one construction in accordance with the invention has been applied.

Figure 2 is a front elevation partly in section of the same;

Figure 3 is a section through one of the buckets on the line 3, 3 of Figure 2;

The general parts of an elevator or dredge constructed in accordance with the present invention are of the usual construction, the buckets being mounted upon an endless chain which travels over a tumbler at the upper end. The buckets come up filled and in passing over the tumbler they are inverted and discharged of the material which they contain into a chute, in the usual way.

Referring to Figures 1 and 2, 10 represents the upper tumbler provided with flanges 11 for retaining the bucket chain upon it. The links 12 of the bucket chain are shown as formed integral with the buckets 13. Each bucket 13, viewed in plan, that is to say, looking into the bucket as shown in Figure 2, is of a more or less oval contour, provided on the outer side with a cutting lip 14. On the side next to the chain it is provided with two water channels 15, cast or otherwise formed in the thickness of the bucket wall. Each channel extends from an open mouth 16 close to one side of the chain down the side of the bucket to the bottom thereof. The channels converge towards one another as they approach the bottom of the bucket and each channel becomes wider as it proceeds, and finally opens into the bottom of the bucket in the form of a wide flat port 17. The two ports 17 lie at

an angle to one another and are situated in a depression 18 in the bottom of the bucket close to the edge 19 of the depression so that clay entering the bucket, at the 5 moment of its excavation, from the cutting lip 14 tends to separate from the bucket wall at the edge 19 of the depression and to leave a cavity opposite the ports 17, to which water may later on be admitted when the 10 time comes for the bucket to be discharged.

The ports 17 are crossed at intervals by bars 20 which lie parallel to the direction of movement of incoming clay and further tend to keep the ports clear. The width of 15 the ports and the spaces between the bars 20, and indeed the whole of the channel 15, are made slightly greater in dimensions than the mouth 16 of the channel so that in the event of a stone or other obstruction 20 entering the mouth of the channel it may not wedge in the channel.

The nozzles 21 are located adjacent to the upper tumbler 10 of the dredger opposite the point of discharge of the buckets 13 and 25 in line with the mouths 16 of the water-channels. These nozzles project from the side of a large transverse water-pipe 22 which is reduced at its ends and passes through bearings 23. A water-supply is led 30 into the pipe 22 from a pipe 24 through a union 25 the connection being such as to permit a suitable arc of movement in the bearings 23 of the pipe 22. The pipe 22 is made of sufficient diameter to reduce eddies in the 35 water stream passing through it so that the water-jets which issue from the nozzles 21 may be free of any tendency to break into spray. Any suitable construction of nozzle 40 may be used which ensures a close jet of water.

Upon the upper tumbler 10 there is mounted a cam 26 having a number of cam projections 27 which correspond with the 45 number of sides of the upper tumbler. A lever 28 projects from the pipe 22 and carries a cam roller 29 for engaging the cams 27. The cam roller 29 is kept in engagement 50 with the cams by the action of a counterweight 30 upon a balance-arm 31 projecting from the pipe 22.

The relative proportions of the parts and the shape of the cams 27 are so arranged 55 that the nozzles 21 are moved during the passage of each bucket past the point of discharge so as to maintain the jets impinging upon the mouths 16 (as indicated in chain lines at A, Figure 1) over as long a period as possible of the passage of the buckets past the jets. As soon as a bucket 60 has fully passed the point of discharge the roller 29 becomes disengaged from the tip of the cam 27 and the nozzle is swung back by the counterweight 30 to a position in which the roller 29 lies against the base 65 of the next cam 27, which positions the noz-

zle so that the jet impinges upon the mouth 16 of the channel 15 in the next bucket.

Instead of the cams 27 any form of striker or equivalent device might be employed and of course, instead of mounting 70 the cam, striker or the like upon the upper tumbler, it might be carried by any part which is operatively connected therewith.

As the buckets ride over the tumbler they are approximately centered thereon by the 75 flanges 11, but it is impossible to ensure accurate centering owing to the weight and size of the parts, wear on the flanges 11, the necessity for providing suitable working clearances and the possibility of the dredge 80 working at a list which may cause the buckets to keep to one side of the tumbler. It is important, however, that the jets from the nozzles 21 should always be accurately centered upon the mouths 16 of the channels in the buckets. To this end, a centering device is provided which comprises a 85 feeler in engagement with the bucket chain and operative connections between the feeler and the jets 21. In the construction illustrated the feeler takes the form of a flanged idler roller 32 in engagement with the underside of the bucket chain close behind the upper tumbler. The flanges 33, 34 of the idler roller are made to fit the sides of the 90 bucket chain closely and to this end the flange 34 is made adjustable longitudinally upon the body of the roller 32 by a screw-thread and locking-nut 35, or by other means. The idler roller is supported in 95 bearings, not shown, by a spindle 36 (Figure 2). The end of the spindle 36 is provided with a grooved collar 37 which receives shoes 38 pivoted on a yoke 39 (Figure 1) of a lever-arm 40. The lever-arm 40 100 is mounted on a shaft 41 which extends at right-angles to the spindle 36 toward the nozzles 21. At the other end of the shaft 41 it carries a second lever 42 having a yoke 43 which carries shoes 44 for engagement 105 with a grooved collar 45 on the end of the pivoted pipe 22 (see Figure 2). A suitable amount of end play is allowed for the pipe 22 in the bearings 23 and thus any lateral movement of the chain is transmitted 110 from the feeler roller 32 through the shaft 41 to the nozzles 21 and the water-jets are kept properly centred.

It is contemplated that a high pressure water-jet should be used, pressure being of 115 the order of 25 pounds or more per square inch, and that the pressure caused by the introduction of this high pressure water to the underside of the clay in the bucket will be sufficient to dislodge the same and to prevent 120 any tendency to retain the clay matter by suction in the bucket.

While the invention has been described with reference to a bucket dredge it will be evident that the application of the invention 125 130

is not limited to such dredges but that it may be employed for freeing any buckets which are liable to become clogged from any materials which they may contain. For example, the skips of mechanical shovels, skips mounted upon a crane, or smaller buckets, in whatever connection employed, may all be constructed with water channels and emptied in accordance with the present invention.

I claim:—

1. A bucket for the reception of materials of the kind described having a passage for admission of water which extends down the side of the bucket and opens into its interior near the bottom for the purpose described, the opening of the passage at the bottom of the bucket being such as to prevent the passage becoming filled with material from the bucket.

2. In a bucket elevator or dredge, the combination of a chain of buckets, channels in the buckets which are provided with mouths outside the buckets and which channels extend from the mouths to the interior of the bucket near the bottom thereof, and a nozzle for a water-jet situated at the approach to the point of discharge of the buckets for directing water into the mouths of the channels for the purpose described.

3. A bucket elevator or dredge as claimed in claim 2 wherein means are provided so to move the nozzle during the passage of each bucket past the point of discharge as to lengthen the periods of impingement of the jet upon the mouths of the channels.

4. A bucket elevator or dredge as claimed in claim 2 wherein the mouths of the channels face forwardly in the direction of movement of the buckets, and the axis of the nozzle lies in the plane of movement of the mouths of the channels to which it directs the water-jet and outside the bucket path.

5. In a bucket elevator or dredge, the combination of a chain of buckets, channels in the buckets which are provided with mouths outside the buckets which mouths face forwardly in the direction of movement of the buckets, the channels extending from the mouths to the interior of the buckets near the bottom thereof, a nozzle for a water-jet the axis of which lies in the plane of move-

ment of the mouths of the channels to which it direct the water-jet from outside the bucket path, and means to move the nozzle in the said plane during the passage of each bucket past the point of discharge so as to lengthen the periods of impingement of the jet upon the mouths of the channels.

6. A bucket elevator or dredge as claimed in claim 2 wherein means are provided so to move the nozzle during the passage of each bucket past the point of discharge as to lengthen the periods of impingement of the jet upon the mouths of the channels, said means comprising a pivotal mounting for the nozzle, an operating lever thereon and a cam operatively connected to the bucket chain for actuating the lever.

7. In a bucket elevator or dredge, the combination of a chain of buckets, channels in the buckets which are provided with mouths outside the buckets which mouths face forwardly in the direction of movement of the buckets, the channels extending from the mouths to the interior of the buckets near the bottom thereof, a nozzle for a water-jet the axis of which lies in the plane of movement of the mouths of the channels to which it directs the water-jet from outside the bucket path, means to move the nozzle in the said plane during the passage of each bucket past the point of discharge so as to lengthen the periods of impingement of the jet upon the mouths of the channels said means comprising a pivotal mounting for the nozzle, an operating lever thereon and a cam operatively connected to the bucket chain for actuating the lever.

8. A bucket elevator or dredge as claimed in claim 2 wherein means are provided for causing the water-jets to move laterally so as to follow any lateral movements of the bucket chain and maintain the supply of water to the channels.

9. A bucket elevator or dredge as claimed in 5 wherein means are provided for moving the jets laterally which comprise a feeler in engagement with the bucket chain and operative connections between the feeler and the nozzle of the water-jet.

In testimony whereof I affix my signature.

FRANK HERNAMAN COTHAY.
